UNITED STATES PATENT OFFICE.

WILLIAM A. BOCK, OF CHICAGO, ILLINOIS, ASSIGNOR TO WILLIAM H. MINER, OF CHAZY, NEW YORK.

SIDE BEARING.

1,290,059.

Specification of Letters Patent.

Patented Jan. 7, 1919.

Application filed August 20, 1917. Serial No. 187,200.

To all whom it may concern:

Be it known that I, WILLIAM A. BOCK, a citizen of the United States, residing at Chicago, in the county of Cook and State of Illinois, have invented a certain new and useful Improvement in Side Bearings, of which the following is a full, clear, concise, and exact description, reference being had to the accompanying drawings, forming a part of this specification.

This invention relates to improvements in side bearings.

The object of the invention is to provide an anti-friction roller side bearing more particularly adapted for railway cars wherein the anti-friction element travels on a curved track, the center of curvature of which corresponds to the center of the pivoted car bolsters, the anti-friction element having provision also for a tilting movement to thereby insure proper contact between the parts at all times.

In the drawing forming a part of this specification, Figure 1 is a top plan view of a side bearing illustrating my improvements, part of the view being shown in section, the section corresponding to the line 1-1 of Fig. 2. Fig. 2 is a vertical, sectional view taken substantially on the line 2-2 of Fig. 1. And Fig. 3 is a detail plan view of the controller arm.

In said drawings, 10 denotes the top portion of a truck bolster to which my improved side bearing is preferably attached. 35 The side bearing, as shown, comprises a main or base casting A having lugs 11-11 at the corners thereof by which it is riveted to the truck bolster; a curved track 12; upstanding concentric curved guide walls 13 and 14; an upwardly offset housing 15; an anti-friction roller B; a controller arm C; and a spring D.

As clearly appears from the drawing, the track 12 is curved on a radius corresponding to the distance from said track to the center of the bolsters between which the side bearing is placed. At its ends, the track 12 is provided with upstanding walls 16-16 by which the movements of the roller are limited. As more clearly appears from Fig. 2, the track 12 is provided at its center with a rib 17 having an upper convex surface and at either side of said rib, the track is beveled downwardly, as indicated at 18-18.

55 The anti-friction roller B, which is of trun-

cated conical form in order to insure proper rolling on the curved track 12, is provided with a centrally located circumferential groove 19 having a concave surface fitting the convex rib 17. The rib 17 and groove 60 19 are so designed that the roller B is permitted a tilting action on the rib with respect to the base casting in vertical planes passing through the usual king pin which pivotally connects the car truck with the car 65 body. The degree to which the roller B may tilt is limited by engagement of the end portions of the roller B with either of said beveled surfaces 18-18.

With this arrangement, it is obvious that 70 the roller may accommodate itself to the bearing surface 20 of the body bolster regardless of the angle between the surfaces of the truck and body bolsters. The housing 15, as shown, has an upper wall 21, 75 lower wall 22, back walls 23-23 and curved side walls 24-24. The controller arm C is pivotally mounted within said housing as by means of the rivet 25. Said controller arm C is provided at its outer or free end 80 with an ellipsoidal shaped portion 26 which is extended within a corresponding recess 27 on the interior of the roller B. Said recess 27 is made of such a shape and size as to permit the necessary tilting of the 85 roller with respect to the controller arm and the curvature of the interior surface of the roller and the portion 26 of the controller arm is designed so that in all positions of the roller and arm, there is a bearing contact therebetween at a point centrally of the roller so that tendency to skew the roller in returning it to normal is minimized.

Intermediate its ends, the controller arm 95 C is provided with upper and lower arc-shaped walls 28-28 connected at their extreme ends by vertical portions 29-29. Said walls 28 are made concentric with the pivotal axis of the arm C and are adapted 100 to have seated therewithin said spring D. The spring D is provided at its ends with followers 30-30 which normally engage upstanding portions 31-31 of the base casting. On their outer faces, the followers 30 105 are provided with projections 32 which seat within corresponding recesses 33 on the inner sides of the vertical portions 29 of the controller arm.

The normal position of the parts is as 110

shown in the drawing. When the truck bolster swings with respect to the body bolster and pressure is exerted on the roller, it is obvious that the latter will roll bodily 5 to one side of its central normal position. This action will cause the oscillation of the controller arm C which will move one of the followers 30 toward the opposite follower, thus compressing the spring D. Upon release of the pressure from the roller B, the spring D will expand and return the arm C to central position and the arm in turn will return the roller.

With the arrangement herein described, 15 it is obvious that proper contact between the roller and its adjacent parts is always obtained and in the returning action of the controller arm, tendency to twist the roller is minimized.

20 I claim:

1. In a side bearing for cars adapted to be placed between two pivotally connected bolsters, the combination with a member having a roller track, said track having a radius 25 of curvature corresponding to the distance from the pivotal connection of the bolsters, a truncated conical roller adapted to roll over said track, and spring controlled means for returning the roller to normal position 30 after each actuation, said roller and track having coöperating means permitting the roller to tilt in any vertical plane passing through a radius of said curved track.
2. In a side bearing for railway cars, the 35 combination with a base casting having a curved roller track, of a roller mounted on

said track, a controller arm pivoted to said base casting and having its free end extending within a recess of the roller, spring means coacting with said arm to center the 40 latter, said arm and roller having coöperating bearing surfaces arranged to insure contact therebetween centrally of the roller in all positions of the latter.

3. In a side bearing, the combination with 45 an antifriction roller, of a member upon which the roller travels; said roller and member having means permitting tilting of the roller, a spring-controlled arm extending within said roller and adapted to return the 50 latter to normal position after each actuation thereof, said roller being rotatable and tilttable with respect to said arm.

4. In a roller side bearing, the combination with a base member having a curved track, 55 said track being provided with a central rib and oppositely and downwardly beveled surfaces on either side of the rib, of a truncated conical roller, said roller having a circumferential groove coöperable with said 60 rib for thereby adapting the roller to tilt in addition to its rolling movement, and means for automatically returning the roller to normal position after each actuation thereof.

In witness that I claim the foregoing I 65 have hereunto subscribed my name this 29th day of July 1917.

WILLIAM A. BOCK.
